Primary Examiner — Kelley Donnelly(74) *Attorney, Agent, or Firm* — Mark M. Friedman(57) **CLAIM**

The ornamental design for a crate, as shown and described.

DESCRIPTION

FIG. 1 is a front view of a crate showing my design;

FIG. 2 is a side view thereof;

FIG. 3 is a top view thereof;

FIG. 4 is a bottom view thereof; and,

FIG. 5 is an isometric view thereof.

The broken lines are for the purpose of illustrating the environment of the article and form no part of the claimed design.
